UNITED STATES PATENT OFFICE.

DAVID STEELE WALLACE, OF DENVER, COLORADO, ASSIGNOR TO THE WALLACE PLUMBING IMPROVEMENT COMPANY, OF SAME PLACE.

DESIGN FOR A WATER-CLOSET BOWL.

SPECIFICATION forming part of Design No. 26,995, dated April 27, 1897.

Application filed September 24, 1896. Serial No. 606,901. Term of patent 14 years.

To all whom it may concern:

Be it known that I, DAVID STEELE WALLACE, a citizen of the United States of America, residing at Denver, in the county of Arapahoe and State of Colorado, have invented certain new and useful Improvements in Designs for Water-Closet Bowls; and I do declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 is a perspective view of a water-closet bowl which embodies my design. Fig. 2 is a perspective view of a central longitudinal section of Fig. 1, showing my design for a water-closet bowl. Fig. 3 represents a cross-section of the flushing-inlet nipple of the flushing-rim of my design for a water-closet bowl.

The leading feature of my design is a water-closet bowl of substantially the configuration and representation shown in the accompanying drawings.

My design comprises an oval bowl K, the top edge of which is rounded over and depends upon the inside and forms a hollow or flushing rim L. At the rear of the bowl a projecting hollow inlet nipple-shaped member O is formed, which is substantially elliptical in cross-section, the extreme end of which is formed into a wedge-shaped annulet or ring P. This inlet member connects with the hollow-rim member of the bowl.

The exterior surface of the bowl is entirely free from projecting ribs and is blended harmoniously with a flat smooth surface from a graceful curve at the back Q into the base R of the bowl. The depression S is not neces-

sarily formed in the side, but is used to economize in the porcelain.

In the bottom of the inside of the bowl and through its base portion an outlet-opening M is formed by a vertically-partitioned-like member A, which is formed in the base portion of the bowl a short distance from the rearward part of the inner surface of the bowl, the outlet M being continued by a passage D, which extends up one side of the member A and over its top edge B, which is formed flat and straight across. The floor portion C of the member A is also flat near its top edge B. Below the member A of the bowl another flat partition-like member F is formed in the base, the space between these two members of the bowl, A and F, forming a continuation of the outlet-passage D of the bowl. The member F of the bowl terminates in a straight transverse edge E. Opposite this edge E a curved partition member G is formed in the base portion of the bowl. This partition member of the bowl defines the outlet-passage member of the bowl around the edge E of the member F. Opposite the lower edge H of the member G a reverse curve I is formed on the opposite side of the bowl's outlet-passage below the terminal edge of the member F, and from the points H and J the outlet-passage member of the bowl extends directly through the base portion R of the bowl.

What I claim is—

The design for a water-closet bowl substantially as shown and described.

In testimony whereof I affix my signature in presence of two witnesses.

DAVID STEELE WALLACE.
